COMBINED TRIM BAR AND NAME PLATE HOLDER FOR AN AUTOMOBILE

Edward O. Sheard, Detroit, Mich., assignor to Chrysler Corporation, Highland Park, Mich., a corporation of Delaware

Application August 13, 1949, Serial No. 4,459

Term of patent 7 years

(Cl. D14—18)

To all whom it may concern:

Be it known that I, Edward O. Sheard, a citizen of the United States, residing in the city of Detroit, county of Wayne, and State of Michigan, have invented a new, original, and ornamental Design for a Combined Trim Bar and Name Plate Folder for an Automobile, of which the following is a specification, reference being had to the accompanying drawing, forming part thereof, in which:

Fig. 1 is a top plan view of my novel combined trim bar and name plate holder;

Fig. 2 is a front elevation thereof;

Fig. 3 is a side elevation of the combined trim bar and name plate holder; and

Figs. 4 and 5 are vertical sections taken on the lines 4—4 and 5—5 of Fig. 2.

I claim:

The ornamental design for a combined trim bar and name plate holder for an automobile, substantially as shown.

EDWARD O. SHEARD.
